(57) **CLAIM**

The ornamental design for a digital multimeter enclosure, as shown and described.

DESCRIPTION

FIG. 1 is a top front right perspective view of a digital multimeter enclosure showing our new design.

FIG. 2 is an inverted bottom rear left perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof.

FIG. 8 is a bottom plan view thereof.

FIG. 9 is a top front right perspective view of the digital multimeter enclosure shown in FIG. 1, with a rear feature cover and a stand shown in an extended position.

FIG. 10 is an inverted bottom rear left perspective view thereof.

FIG. 11 is a front elevational view thereof.

FIG. 12 is a rear elevational view thereof.

FIG. 13 is a left side elevational view thereof.

FIG. 14 is a right side elevational view thereof.

FIG. 15 is a top plan view thereof; and,

FIG. 16 is a bottom plan view thereof.

The broken lines in the figures illustrate environment only and form no part of the claimed design.
